METALLIC RECEPTACLE AND CLOSURE
THEREFORWilliam Lockhart, Cleveland, Ohio, assignor to
Cornell Securities Corporation, Cleveland,
Ohio, a corporation of Delaware

Application March 1, 1934, Serial No. 713,461

3 Claims. (Cl. 220—61)

This invention is an improvement in metallic receptacles or containers, and relates more particularly to closures therefor and means for removably securing the closures in place to effect a fluid-tight seal between the receptacle and the closure.

In shipping metallic receptacles of the full removable head type, it has been found desirable to provide a clamping device by means of which the cover may be clamped in place with only sufficient security to prevent accidental removal thereof in shipment, as, for instance, where the empty containers are shipped from the manufacturer to the user. It is also desirable in this event, to apply only sufficient closing pressure on the receptacle and the gasket separating the cover flange from the head of the receptacle, to hold the parts together without fully setting or compressing the gasket, so that when the receptacle is filled with its charge and the shipper desires to more effectively clamp the cover thereon in a fluid-tight seal, this may be done conveniently by further pressing the cover flange down upon the gasket to press the latter further against the bead.

It is, therefore, one of the objects of this invention to provide a closing or clamping device for removably securing a cover on a metallic container such as a barrel, drum or the like, to effect a fluid-tight seal between the cover and the receptacle, without the aid of tools.

Another object of the invention is to provide means for imparting a closing pressure uniformly along the cover flange and the bead of the receptacle to bring the same together in fluid-tight relation and at the same time to apply such closing pressure in a selective and predetermined manner.

A further object of this invention is to seal the cover in place against unauthorized or accidental removal.

A still further object of the invention is to construct a clamping ring or device for securing covers on metallic receptacles which is simple of construction, extremely durable and inexpensive to manufacture, and which does not require the use of separate tools for its application.

Other objects and advantages of my invention will become more apparent as the following description of an embodiment thereof progresses, reference being made to the accompanying drawing, in which like reference characters are employed to designate like parts throughout the same.

In the drawing:—

Figure 1 is a top plan view of one embodiment of my invention, showing the cover clamped in place on a receptacle in fluid-tight sealed relation;

Figure 2 is an enlarged fragmentary section taken on line 2—2 of Figure 1;

Figure 3 is a fragmentary plan view of the adjacent ends of the clamping or locking ring, showing the same contracted to seal the cover on the receptacle. In this view the clamping ring has been contracted to its maximum to exert the greatest pressure upon the cover flange and the bead of the receptacle;

Figure 4 is a view similar to that shown in Figure 3 except that the degree of contraction of the clamping device is that used when the drum is shipped empty;

Figure 5 is a cross sectional view taken on line 5—5 of Figure 3;

Figure 6 is a cross sectional view taken on line 6—6 of Figure 3;

Figure 7 is a fragmentary view similar to the views shown in Figures 3 and 4, and shows the locking lever released to permit expansion of the locking ring; and

Figure 8 is a section taken on line 8—8 of Figure 1.

While my invention is particularly applicable to metallic containers or receptacles such as barrels, drums and the like, which are provided with a circumferential bead at their open end for receiving and supporting a cover and for reinforcing purposes, it is to be understood that I do not limit the invention in this respect since the same may be applied to other types of receptacles or containers.

In the accompanying drawing I have illustrated one embodiment of the invention and have shown the same applied to a metallic shipping drum 1. The upper edge of the drum or container is rolled to form a peripheral bead 2 at its open end. A cover 3 comprising a cupped member having a peripheral upwardly and outwardly extending flange 4, supported by the bead 2 and the packing 5 in such a manner that the cupped portion of the cover may be telescoped for a short distance within the open end of the container, is illustrated in Figure 2. It will be noted that a portion of the flange 4 is slightly arcuate in cross section to conform with the approximate curvature of the upper surface of the bead, and that the outer edge of the flange terminates at a point near that defined by the greatest outside diameter of the bead. 55

The packing 5 may consist of an annulus of any suitable packing material such as rubber or cork. I find cork to be very satisfactory in use.

It is desirable that the cover be removably secured on the receptacle in such a manner that a fluid-tight seal between the cover, the packing and the bead may be made.

By means of my invention a fluid-tight seal between these parts is readily accomplished, as 10 a further description of the embodiment of my invention shown in the drawing will reveal. According to the present invention one simple means for removably securing the cover on the receptacle in fluid-tight relation may include a 15 split contractible channeled clamping ring 6 which is substantially U-shaped in cross section and in which the upper and lower flange and bead engaging walls respectively of the ring converge outwardly toward the arched portion 20 such as is indicated more clearly in Figure 2.

While I have described a ring which is contracted to press the cover into sealing relation with the receptacle, it is to be understood that the invention may be equally well applied to a 25 ring which is expanded to press these parts together.

It will thus be seen that by contracting the ring, the cover flange 4 will be pressed tightly against the packing 5 and the supporting bead 30 2 under a closing pressure exerted thereagainst uniformly throughout the circumference of the ring.

The contractible, channeled ring 6 is substantially U-shaped in cross section and is split 35 transversely, preferably at one point as indicated in Figure 1. Lugs 8 and 8' extend inwardly from the ring ends defining the split and may be formed integrally with the ring end or may be formed separately and welded thereto.

In further carrying out the invention I have 40 provided means for contracting and expanding the ring about the open end of the receptacle to removably secure the cover in place, and such means may consist of an operating lever 9 pivoted at 10 to the lug 8. The lever 9 is provided 45 with an operating handle portion 11 which is preferably arched to conform to the curvature of the receptacle wall. The lever 9 is preferably slotted or cut away as at 12 in the form of a substantially L-shaped slot for purposes which 50 will be more fully described hereinafter although this slot may be cut directly out of the forward edge of the lever as distinguished from the body portion between the forward and rearward edges. Adjacent the cut-away portion 12 of the lever 55 it is desirable to provide additional lever material to strengthen the same on one of its sides. This may be done by permitting a portion of the lever material to project rearwardly as at 13.

The lever is connected with the opposite end 60 of the split contractible ring by means of one or more links 14. While it is possible to employ the use of but one link 14 connecting the lever with the other end of the ring, I have found it 65 to be more desirable to employ two such links 14 operating on opposite sides of the lever and on opposite sides of the lug 8' to which they are pivotally connected as at 15.

The opposite ends of the links 14 are connected by means of a headed pin or rivet 16 70 which is adapted to pass through and operate within the cut out or notched portion 12 of the lever 9.

It will be noted that the cut out portion 12 of 75 the lever is substantially L-shaped and pro-

vides two seats or bearing recesses 17 and 18 for receiving the pin 16. As illustrated in the drawing, when the pivot pin 16 is placed to operate in the seat 17 (Figure 4), and the lever is moved to the position shown, the ring will be contracted to only partially press the cover down on the receptacle. As pointed out above, this adjustment is employed in shipping the drums empty and where it is not desired to fully set the gasket to provide a fluid-tight seal. 10

However, when such a seal is desired, the links are placed so that the pin 16 operates in the seat 18 representing a greater radius on the axis 10 than the radius between the axis 10 and the seat 17. Due to the greater radius of the throw, 15 when the pin is in the position shown in Figure 3, the degree of contraction of the ring will be increased somewhat, and the pressure exerted upon the bead 5 and the cover flange 4 will be increased sufficiently to insure a fluid-tight seal 20 between the cover and the bead.

The lever 9 may be provided with a projection or shoe 20 adapted to engage the inner upright wall of the cover under increasing pressure as the lever is moved toward full ring contracting position. In this manner the closing pressures are found to be more evenly distributed about the periphery of the ring since as the shoe begins to engage the cover, the substantially diametrically opposite side of the ring will first be pressed 30 firmly in place, while increased pressure of the shoe against the cover as the lever is moved, will cause the closing pressures to gradually and uniformly creep around both sides of the ring toward the point where the shoe is in engagement with the cover. 35

While I have not shown in the drawing an application of the pivot adjustments 17 and 18 to the pivotal connections 10 and 15, it is to be understood that I intend such applications to be 40 contemplated by this invention.

For instance, the pivot connection 10 of the lever with the lug 8, instead of being fixed as shown may be in the form illustrated at 17 and 18, that is, the fulcrum of the lever may be 45 shifted to a plurality of positions to predetermine the extent of the lever throw and thus determine the force of the contracting pressures applied to the ring and cover flange and bead. Likewise, the pivot connection 15 between the 50 links and the other lug 8' may be similarly designed for such adjustment. Furthermore, the cut away portions 17 and 18 need not be located within the lever, but may be formed along the outer edge thereof in a series of 55 notches.

From the above description, it will be noted that my invention provides for a simple clamping device for removably securing a cover on a receptacle in fluid-tight relation, and that the 60 same is easy to operate without the aid of separate tools. Furthermore, the invention provides for such a device which is extremely sturdy and capable of exerting tremendous pressures to press the cover flange and bead together when a 65 fluid-tight seal is desired, while the device may be selectively adjusted and operated to exert lesser pressures on these parts such as may be required to prevent accidental displacement of the cover in shipping the receptacles empty 70 from the manufacturer to the user.

Various changes in the details of construction and arrangement of parts may be made without departing from the spirit of my invention or the scope of the appended claims. 75

I claim:

1. In a clamping device for a metallic receptacle having a bead rolled about its open end and a cover having a flange fitting over the bead, a contractible channeled clamping ring having portions engaging the bead and cover flange to press the same together when the ring is contracted, and means for contracting the ring including a lever pivotally connected with a portion of the ring and a link pivotally connecting said lever with another portion of the ring, said lever having an L shaped slot formed therein for adjustably receiving an end of said link.
2. In a clamping device for heavy gauge metallic shipping receptacles having a bead rolled about its open end and a cover having a flange fitting over the bead, a transversely split contractible channeled clamping ring having portions engaging the bead and cover flange to press the same together when the ring is contracted, and means for contracting the ring including a lever pivotally connected with an end of the ring for horizontal movement in the plane of the ring, said lever having an L shaped slot therein, and a member connecting the other end of the ring with said lever and having a portion slidable in said slot to selectively engage the extremities thereof.
3. In a clamping device for heavy gauge metallic shipping receptacles having a bead rolled about its open end and a cover having a flange fitting over the bead, a transversely split contractible channeled clamping ring having portions engaging the bead and cover flange to press the same together when the ring is contracted, and means for contracting the ring including a lever member pivotally connected with an end of the ring for horizontal movement in the plane of the ring, and a member connecting the other end of the ring with said lever, one of said members having an L shaped slot formed therein and the other member having a portion slidable in said slot to selectively engage the extremities thereof.

WILLIAM LOCKHART.
